UNITED STATES PATENT OFFICE

2,656,653

GRINDING MACHINE WITH WHEEL SURFACE POSITION INDICATOR

Ralph D. Gardner, Roscoe, Ill., assignor to Gardner Machine Company, South Beloit, Ill., a corporation of Illinois

Application December 16, 1950, Serial No. 201,081

12 Claims. (Cl. 51—165)

1

The present invention relates generally to the field of machine tools and more specifically to a novel grinding machine having means whereby one or more of the abrading elements therein may be positioned with nicety and precision.

The invention finds particular, but by no means exclusive, utility when embodied in a machine having opposed abrasive wheels adapted to operate simultaneously on both sides of the work. Such a machine is disclosed, for example, in United States Patent No. 2,142,444, issued January 3, 1939, to Donald R. Hall.

In a grinding machine, the work-engaging surface of the abrasive wheel tends to change position due to wear which occurs as the machine is operated. Where work is being ground to a predetermined dimension, periodic adjustment of the position of the abrasive wheel is necessary if such dimension is to be maintained. Since the work-engaging surface might not wear uniformly, the usual practice is to dress such surface prior to repositioning the wheel. After the dressing operation, if such be performed, or after a given period of use in the event the wheel is not dressed, a predetermined repositioning adjustment is imparted to the wheel. Such adjustment is predicated upon an approximation of the amount of material removed from the work-engaging surface of the grinding wheel and positions the latter where the operator thinks it should be. In ordinary grinding machines, this sort of adjustment is sufficiently accurate for certain classes of work in which a high degree of precision is not required.

In a machine of the character disclosed in Hall Patent No. 2,142,444, where the opposed faces of a pair of abrasive wheels operate simultaneously on both sides of the work, a number of difficulties are apt to be encountered when repositioning adjustment of the wheels is effected in the manner outlined above. Moreover, when the abrasive wheels of such a machine are closely spaced for precision grinding of piston rings or other relatively thin workpieces which are moved in a procession along a pair of spaced apart guide bars located between the wheels, conventional wheel positioning techniques aggravate such difficulties. At the outset, it will be observed that a variable which tends to upset the accuracy of a fixed compensating adjustment for each wheel is injected due to the improbability that the amount of wear on the grinding face of one wheel will be identical with the amount of wear on the grinding face of the other wheel. Dressing of the grinding faces not

2

only fails to eliminate this variable, but, in addition, the dressing operation is apt to inject still another variable due to the fact that the dressing tool will itself experience an appreciable amount of wear unless it is a diamond. Consequently, when the wheels are repositioned after the dressing operation by the application of a fixed adjustment based on an approximation of wear, there is a definite possibility that improper spacing between the two grinding faces will occur. There is also a definite possibility that the wheel spacing will be unbalanced or off center with respect to the guide bars which extend between the opposed grinding faces. In other words, the guide bars will be located closer to one of the opposed grinding faces than to the other. Since grinding machines of the foregoing character usually have their wheels enclosed, the operator is unable to observe the wheels when making his compensating adjustments for positioning them. Under such circumstances, the grinding face of one of the wheels is apt to make contact with the guide bars, resulting in spoilage of the latter, spillage of the workpieces, and considerable down time of the grinding machine.

One object of the invention is to provide a grinding machine including means for apprising the operator as to the arrival of the work-engaging surface of the abrasive element or elements at a preselected, predetermined position during adjustment of such element or elements.

Another object is to provide a grinding machine having means for precisely determining the extent to which material has been removed from the work-engaging surface of one or more of its abrasive elements due either to wear or to a dressing operation.

A further object of the invention is to provide a grinding machine of the character set forth and wherein the abrasive element or elements can be readily positioned for dressing and repositioned with nicety and precision after dressing, permitting accurate maintenance of a predetermined dimension in the work.

Still another object is to provide a novel wheel surface position indicator susceptible of use in effecting repositioning of one or more of the abrasive elements or of precisely controlling infeed operations of these elements.

Other objects and advantages of the invention will become apparent as the following description proceeds, taken in connection with the accompanying drawings, wherein:

Figure 1 is a front elevational view of an illus-

trative grinding machine embodying the present invention, such machine having a pair of closely spaced, opposed grinding wheels indicated in broken outline.

Fig. 2 is an enlarged vertical sectional view of the machine shown in Fig. 1, such view being taken in the plane of the line 2-2.

Fig. 3 is an enlarged fragmentary vertical sectional view showing the right-hand half of the machine of Fig. 1 and taken approximately along the longitudinal metal plane of the machine.

Fig. 4 is an enlarged fragmentary vertical sectional view taken in the plane of the line 4-4 in Fig. 1 and detailing a portion of the indicator means.

Fig. 5 is an enlarged fragmentary broken sectional view through a portion of the indicator means, such view being taken in the plane of the line 5-5 in Fig. 4.

Figs. 6 and 7 are enlarged fragmentary horizontal sectional views taken through the right-hand half of the machine of Fig. 1 and in the plane of the line 6-6 in Fig. 3.

Fig. 8 is an enlarged fragmentary vertical sectional view taken through a portion of the mechanism shown in Fig. 7 and in the plane of the line 8-8.

While the invention is susceptible of various modifications and alternative constructions, a preferred embodiment has been shown in the drawings and will be described below in considerable detail. It should be understood, however, that there is no intention to limit the invention to the specific form disclosed, but on the contrary, the intention is to cover all modifications and alternative constructions falling within the spirit and scope of the invention as expressed in the appended claims.

Referring more specifically to Fig. 1, the invention is there shown embodied in an illustrative grinding machine 20 of the general type disclosed in Hall Patent No. 2,142,444, referred to above. The machine 20 comprises a box-like base 21 of substantially rectangular shape, together with a pair of beds 22 fixed in spaced apart relation on the top of the base. Each of the beds 22 is of hollow, box-like form and is provided with a channel 24 in its top surface defining a pair of ways 25 running longitudinally of the base 21 (see Fig. 2). Disposed within corresponding ones of the channels 24 and supported for relative sliding movement on the ways 25 are a pair of slides 26 each of which carries one of a pair of substantially identical grinding heads 28. In view of their similarity, a description of one of the heads 28 will suffice for both. Thus there is journaled in suitable bearings within the head 28 a driving spindle 29 terminating at its inner end in a supporting disk 30 and backing plate 31, the latter having fixed thereto an abrasive element in the form of a grinding disk 32. Together, the plate 31 and disk 32 constitute an abrasive wheel 34 (see Fig. 3). The wheel 34 is rotated by suitable means such as motor 35 which transmits power to the end of the spindle 29 remote from the wheel as by means of pulleys 36, 38 and belts 39. In the machine 20, these members are enclosed by means of a protective hood 40. The latter may be utilized to support a coolant bonnet 41 which is adapted to introduce fluid coolant into an axial passage (not shown) in the spindle 29 which conducts it to the abrasive wheel 34.

Due to the fact that the structure just described is duplicated in the other grinding head

28 and its associated drive means, it will be appreciated that the abrasive wheels 34 are located in closely spaced relation and define a grinding zone centrally of the machine 20. In the present instance, both of the wheels 34 and the grinding zone are enclosed within a splashproof protective housing 42 of substantially rectangular form.

For the purpose of channeling a procession of workpieces, such as piston rings R, through the grinding zone, the machine 20 is equipped with a pair of vertically spaced guide bars 43 running substantially horizontally through the grinding zone and along a diametrical axis (see Figs. 2 and 3). The guide bars 43 are adjustably fixed to the housing 42 and under normal operating conditions are centered in the space between the grinding faces 44 of the abrasive wheels.

In order to position the abrasive wheels 34 with their grinding faces 44 in properly spaced relation for grinding the workpieces R to predetermined thickness, a suitable adjustable stop means is interposed between each of the grinding heads 28 and its associated supporting bed 22. Since this arrangement is substantially identical for each head, a description of the stop mechanism associated with the right-hand one of the grinding heads 28 (as shown in Figs. 1 and 3) will suffice for both. Referring in particular to Fig. 3, it will be noted that the head 28 has a relatively heavy boss 45 depending from its slide and extending down into the hollow region of the underlying bed. Fixed to the boss 45 as by means of screws 46 is a mounting pad 48 carrying a hollow stop pin 49. The latter is formed with a generally frusto-conical recess 50 complementary to tapered end 51 of an adjustable stop element 52. In this case, the element 52 happens to be integral with an adjusting screw 54 rigidly but adjustably supported within the bed 22. Controlled axial adjustment of the screw 54 and the stop 52 relative to the bed 22 may be effected by rotating the screw within elongated nut 55 fixed to the bed 22. This is accomplished in the machine 20 as by means of a worm wheel 56 splined or slidably keyed upon the screw 54 and disposed in meshing engagement with a worm 58. The latter is secured to a shaft 59 which projects through the front wall of the bed 22 and carries adjusting hand wheel 60 in rigidly fixed relation with its projecting end (see Figs. 1 and 2).

The grinding head 28 may readily be urged in a direction tending to maintain abutting engagement between the stops 49, 52 or in an opposite direction tending to separate the stops. This is accomplished in the present case as by means of a fluid actuator 61. The latter comprises an air cylinder housed within the base 20 and having a piston rod 62 pivotally connected with the depending boss 45 through a rocker arm 64 pivoted on a pin 65 anchored to the machine base. The head 28 is normally biased in a direction tending to maintain the stops 49, 52 in abutting relation. This may be achieved by suitable spring means associated with the actuator 61 or, alternatively, by making the actuator double acting and utilizing pressure fluid to create the biasing force. Since the structure thus far described is duplicated for the other one of the grinding heads 28, it will be appreciated that the abrasive wheels 34 may be moved into grinding position as indicated in dot-dash outline in Fig. 3 by bringing their associated stops 49, 52 into a condition of direct abutting engagement as shown in Fig. 7.

and thereupon adjusting each stop 52 through rotation of its corresponding hand wheel 60 in an appropriate direction.

After a given amount of operation, the grinding faces 44 of the wheels 34 must be dressed to restore their true contour. This is accomplished in the machine 20 by means of a dresser mechanism 66 which in the present instance happens to be mounted on the protective housing 42 enclosing the abrasive wheels. While the details of the dresser mechanism are unimportant for present purposes, it might be stated that the mechanism 66 includes a dressing tool which is adapted to take a relatively light cut as it is moved across the grinding face 44 of each abrasive wheel. Since the thickness of the dressing tool is considerably greater than the distance between the abrasive wheels when in grinding position, it is necessary to retract the wheels 34 from each other to perform the dressing operation. Retraction of each of the wheels 34 may readily be effected by causing the grinding heads 28 to move away from each other and toward the ends of the base 21. This can be done in the machine 20 by controlling each of the actuators 61 in such a manner that its piston rod 62 moves toward the center of the machine.

Once retracted, the wheels 34 and their respective grinding heads 28 may be properly positioned for the dressing operation by interposing a spacer 68 of predetermined length between their adjacent stops 49, 52 and at the same time effecting abutting engagement between such parts by proper control of the actuators 61 and their associated biasing means (see Figs. 3 and 6). Each spacer 68 in this instance comprises a hollow boss 69 having a generally frusto-conical recess 50A at one end similar to the recess 50 and also complementary to the tapered end of the stop 52 against which it abuts. The boss 69 is carried by an arm 70 which, in turn, is rigid with another boss 72 mounted on a shaft 74. The spacer 68 is constrained to move with its associated grinding head 28, and also to rock in response to rocking of the shaft 74, by the use of a sleeve 75 which is fixed thereto. The sleeve 75 passes through an extension of the mounting pad 48 surrounding the shaft 74 and terminates at a collar 76 at its opposite end. The collar 76 is secured to the sleeve 75 as by means of a set screw 78, the inner end of which rides in a keyway 79 running longitudinally of the shaft 74. Thus, the spacer 68 may be swung into and out of operative position simply by rocking the shaft 74 in the appropriate direction. For this purpose, there is fixed to the shaft 74 at one end thereof a depending crank arm 80 pivoted as by means of a pin 81 to the inner end of an operating plunger 82 which projects through the front wall of the bed 22 and terminates in an operating knob 84. Upon reference to Figs. 6 to 8, it will be perceived that when the plunger 82 and knob 84 are pulled outwardly, the spacer 68 is swung upwardly into operative position between the stops 49, 52. Conversely, when the plunger 82 and knob 84 are pushed in, the spacer 68 is swung downwardly into inoperative position. This structure is, of course, identical for each grinding head.

Provision is made in the grinding machine 20 for enabling the operator to bring the work-engaging face 44 of each abrasive wheel into a pre-selected, predetermined position with ease and precision. Referring to Figs. 3, 4 and 5, it will be perceived that this is accomplished by operatively associating with each of the wheels 34 an indi-

cator 85 capable of apprising the operator when the grinding face is located precisely in the desired position. Thus, in repositioning the wheels after a dressing operation, the indicator means 85 permits the operator to adjust the grinding heads until the grinding faces 44 of the wheels are precisely where they should be, rather than merely where the operator thinks they should be. In the present instance, the indicator means 85 comprises a pair of detectors 86 each operatively associated with a corresponding one of the abrasive wheels to define a reference plane for the predetermined position of its grinding face 44, together with a perceptible signal means 88 which may be electrically actuated. As indicated in Figs. 4 and 5, each of the detectors 86 comprises a resilient finger 89 of spring steel or the like terminating at its free end in a hardened tip 90 preferably of toolstock known in the trade as "Carboloy." The finger 89 is supported by means of a bracket 91 and a relatively small diameter rod 92 which passes through a resilient bushing 94 in the bracket, the depending end of the rod 92 being mechanically fixed to the end of the finger 89. Disposed in overlying and supporting relation with the foregoing parts in each of the detectors 86 is a head 95 fixed to a sleeve 96. The latter is slidably housed in a bore 98 in the wheel protective housing 42 running substantially parallel to the rotational axis of the abrasive wheel. Adjustment of each detector 86 in a direction parallel to the rotational axis of the wheel is effected as by means of an adjusting knob 99 having a threaded stem 100 which engages a tapped hole 101 in the housing 42. Mounted on the stem 100 for axial movement therewith as by means of collars 102, but relatively rotatable with respect to the stem, is an arm 104. The latter fits over the end of the sleeve 96 remote from the head 95 and may be fixed relative to the sleeve 96 by means of a set screw 105, the inner end of which tightly engages a groove 106 in the sleeve.

The finger 89 of each detector 86 may be shifted into or out of the path of axial movement of its associated abrasive wheel by the simple expedient of loosening the set screw 105 and rotating the detector assembly within the bore 98 which surrounds the sleeve 96. In order to permit the detector to remain in a given position of angular adjustment, there is associated with each of the sleeves 96 an appropriate friction drag. This may, for example, take the form of a spring-loaded plunger 108 mounted within a bore 109 in the housing 42, the tension of the loading spring 110 being regulated as by means of a closure plug 111.

For the purpose of actuating the perceptible signal means 88 upon arrival of the grinding face 44 at its predetermined position, each of the detectors 86 is equipped with an interesting signal-generating means. Since such means is substantially identical for each detector, a description of one will suffice for both. Turning again to Fig. 5, it will be perceived that the head 95 in the present instance has housed therein an acoustic pickup, preferably in the form of a crystal cartridge 112 similar to the cartridge of a phonograph pickup. Clamped in the crystal cartridge 112 and leading downwardly therefrom is a "needle" member 114 in the form of a relatively stiff but small diameter wire connected at its opposite end to the spool-like upper end 115 of the rod 92. The latter and its point of connection with the needle member 114 are surrounded by a resilient protec-

7
tive boot 116 carried by a hollow boss 118 which constitutes a part of the head 95. The cartridge 112 is connected, preferably by means of shielded wires 119, 120, to an electronic amplifier 121. Acoustic impulses due to contact between the grinding face 44 and the hardened tip 90 on the detector finger are impressed upon the cartridge 112. The crystal element within the latter generates small electrical impulses proportional to the acoustic impulses and these are amplified by the device 121 and delivered as audible sound by means of a loudspeaker 122.

While the operation of the machine 20 and the indicating means 85 is no doubt already apparent to those skilled in the art, a brief synopsis thereof might be helpful at this point. Assume, first of all, that the detectors 86 including the fingers 89 have been adjusted to define the predetermined location for each of the grinding faces 44 and that the fingers 89 are in the path of movement of their associated abrasive wheels. Assume also that the dressing operation has just been completed and that the grinding heads 28 and the wheels 34 are in their retracted position, as illustrated in Fig. 3. Considering first the right-hand one of the grinding heads 28, it will be appreciated that the head can be retracted a slight additional distance by means of the actuator 61 to provide clearance between the stops 49, 52 and the spacer 68. When this has been done, the plunger 82 and its operating knob 84 are pushed inwardly to the position indicated in Fig. 7, swinging the spacer 68 downwardly and into its inoperative position. At this point, the actuator 61 or the biasing means associated therewith is permitted to shift the grinding head 28 toward the guide bars 43, bringing the stops 49, 52 into direct abutment with each other. By carefully rotating the hand wheel 60 at the front of the bed 22, the operator can rotate the stop adjusting screw 54 and cause the stop 52 to retreat slowly in a direction approaching the work with the stop 49 following it in continuous abutting engagement. Such action, of course, serves to shift the grinding head 28, together with its abrasive wheel 34, toward the work-supporting guide bars 43 at the center of the machine, causing the grinding face 44 of the wheel to approach its predetermined position. This adjusting movement is continued until initiation of contact between the grinding face 44 and the hardened tip 90 of the detector finger. The resulting acoustical and electrical impulses due to this contact cause the loudspeaker 122 to emit a sudden raucous sound. At this point, the operator back off on his adjustment over so slightly until this sound is reduced to a low level or disappears entirely, at which point the desired adjustment of the grinding face 44 will have been achieved. The same sequence is, of course, followed for positioning the left-hand grinding head.

While one might suppose that considerable wear would occur on the tips 90 of the detector fingers 89 as they contact the grinding faces 44, it has been found that when Carbolyt tips are used, the wear is negligible even though the contact with the grinding face is maintained over long periods of time. This is probably due to the fact that each of the arms 89 has considerable resiliency and also to the fact that even the barest contact between the tip 90 and the grinding face is sufficient to provide a powerful signal through the speaker 122. If, however, it should be desired to rock the detectors 86 into

8
inoperative position after the grinding wheels and their faces 44 have been precisely positioned, this may readily be done by loosening each set screw 105 and rotating the detectors 86 in the manner already outlined above. By proper proportioning of the parts, such movement can be effected without disturbing the axial adjustment of the detectors 86 produced by the knobs 88.

The susceptibility of the indicating means 85 for use in determining the amount removed from the grinding face of either or both abrasive wheels by a dressing operation will be readily apparent from the foregoing description. This may be facilitated by mounting a calibrated scale (not shown) adjacent each of the adjusting knobs 88 or in proximity to some other movable part of each detector assembly.

Upon reflection, this adaptability of the indicator means 85 for the automatic controlling of infeed of either or both abrasive wheels will also be apparent. For such purpose, the amplifier and perceptible signal means may be connected to the control system of the machine so as to reverse the feed and return the wheels when their grinding faces have reached a predetermined position. If desired, the signal means may be eliminated completely in favor of a direct actuating connection between the amplifier 88 and the control system of the machine.

I claim as my invention:

1. A grinding machine comprising, in combination, a base, a work support on said base, a pair of grinding heads mounted on said base for linear movement relative to the same and to said work support, a pair of abrasive wheels each journaled in a respective one of said grinding heads, each said wheel respectively having an individual grinding face thereon adjacent said work support, means including an adjustable stop interposed between each said grinding head and said base for positioning said individual grinding faces relative to said work support, means for normally biasing said grinding heads toward said work support and for alternatively retracting said heads from said support, a detector supported on said base and having a relatively flat resilient finger disposed in the path of said grinding faces for interception thereof in response to movement of said grinding heads by said adjustable stop means, said finger being adapted to sense arrival of said grinding faces into predetermined positions relative to said work support, and means including a perceptible signal device connected to said detector, said signal device being susceptible of producing a perceptible signal in response to impulses from said finger.

2. A grinding machine comprising the combination of a base, a work support, a grinding head mounted on said base for axial movement relative to said work support and to said base, an abrasive element journaled in said grinding head and movable axially therewith, said abrasive element having a work-engaging surface lying transversely of the direction of axial movement of said grinding head, an adjustable stop means associated with said grinding head for axial positioning of said abrasive element, and its work-engaging surface relative to said work support, means for urging said grinding head against said adjustable stop means, a detector having a relatively flat resilient finger with a hardened metallic tip for sensing arrival of said work-engaging surface into a predetermined axial position relative to said work support in

response to adjustment of said stop means, said resilient finger being disposed transversely of the direction of axial movement of said grinding head, and means including a perceptible signal device connected to said detector, said signal device being susceptible of producing a perceptible signal upon arrival of said work-engaging surface in said predetermined position.

3. A grinding machine comprising the combination of a base, a pair of abrasive wheels mounted on said base and susceptible of relative linear movement toward and away from each other, said wheels having opposed grinding faces, means for adjusting the positions of said abrasive wheels relative to each other, detector means interposed between said abrasive wheels and mounted in close proximity to their respective grinding faces for interception of the same during relative linear adjustment of said wheels, and a perceptible signal means connected to said detector means for actuation by the latter upon arrival of said grinding faces in a predetermined relative position.

4. A grinding machine comprising the combination of a base, a work support, a pair of abrasive wheels mounted on said base in straddling relation with said work support and susceptible of relative axial movement toward and away from said support, said wheels having opposed grinding faces, means for adjustably positioning said abrasive wheels and their grinding faces relative to said work support and to each other, detectors interposed between said abrasive wheels and including means for sensing arrival of their respective grinding faces in predetermined positions during relative axial adjustment of said wheels, and means including a perceptible signal device connected to said detectors for actuation by the latter upon arrival of said grinding faces in said predetermined positions.

5. In a grinding machine, the combination comprising a base, a pair of abrasive wheels having opposed grinding faces and mounted in spaced apart relation on said base, guide means interposed between said grinding faces for channelling workpieces therebetween, a pair of grinding heads for rotatably supporting said abrasive wheels, a pair of beds on said base adapted to support respective ones of said grinding heads and their associated wheels for relative linear movement toward and away from each other as well as toward and away from said guide means, means including an adjustable stop interposed between each said grinding head and its associated bed for positioning a corresponding one of said grinding faces, a pair of detectors supported upon said base and respectively associated with a corresponding one of said abrasive wheels, means including a relatively flat finger carried by each said detector and disposed between said abrasive wheels for interception of an associated one of said grinding faces in response to adjustment of a corresponding one of said grinding heads, each said finger being adapted to sense arrival of the grinding face into a predetermined position relative to said guide means, and means including an electrically actuated perceptible signal device connected to said detectors, said signal device being susceptible of producing a perceptible signal in response to impulses from said finger means.

6. An indicator for use with a grinding machine having an adjustably positionable abrasive wheel with a work-engaging face thereon, said indicator comprising the combination of a sup-

porting member attachable to said machine, a head on said supporting member, an acoustic pick-up protectively enclosed within said head, a signal amplifying device connected with said pick-up, means connected with said amplifying device for producing a perceptible signal in response to mechanical impulses on said acoustic pick-up, a finger disposed for interception of the work-engaging face of the abrasive wheel as an incident to adjustment of the same, and a resiliently mounted rod connected between said finger and said pick-up for transmission of mechanical impulses thereto.

7. An indicator for apprising a grinding machine operator as to the position of the work-engaging face of an abrasive wheel, said wheel being adjustable relative to said machine, said indicator comprising the combination of a supporting member attachable to said machine, a head on said supporting member, an acoustic pick-up within said head, a bracket depending from said head, a resilient finger supported by said bracket and adapted for interception of the work-engaging face of said wheel as an incident to adjustment of the same, means supported by said bracket and connecting said finger with said pick-up, a signal amplifier connected with said pick-up, and means connected to said amplifier for producing a perceptible signal in response to mechanical impulses on said pick-up due to contact between said finger and the work-engaging face of said wheel.

8. An indicator for apprising a grinding machine operator as to the position of the grinding face of an abrasive wheel, said indicator comprising the combination of a supporting member, means for adjusting said supporting member relative to said machine and the grinding face of the abrasive wheel, an acoustic pick-up mounted on said supporting member, a bracket carried by said member, a resilient finger carried by said bracket for interception of said grinding face, means connecting said finger with said pick-up, a signal amplifier connected with said pick-up, perceptible signal means connected to said amplifier, and a mechanical connection on said bracket and interposed between said finger and said pick-up.

9. An indicator for apprising an operator as to the position of the grinding face of an abrasive wheel, said wheel being adjustable relative to said machine, said indicator comprising, in combination, a hollow supporting sleeve attachable to said machine, a head fixed to said sleeve, means for effecting linear adjustment of said sleeve and head along an axis substantially parallel with the direction of adjustment of the abrasive wheel, means for effecting angular adjustment of said sleeve and head about its linear adjustment axis, an acoustic pick-up in said head, a bracket depending from said sleeve, a resilient finger supported by said bracket and disposable into intercepting relation with the grinding face of the abrasive wheel, a hardened tip on said finger, a rod member carried by said bracket and interposed between said finger and said pick-up, an electronic amplifier connected to said pick-up via conductors housed within said sleeve, and a loudspeaker connected to said amplifier for reproducing amplified acoustic impulses resulting from interception of said grinding face by the tip on said finger.

10. The combination of a grinding machine having a pair of closely spaced abrasive wheels and means disposed therebetween for supporting

11

a workpiece, with an indicator means comprising a pair of detectors interposed between said wheels and disposed for interception of respective ones of their grinding faces when the latter are in a predetermined position relative to the workpiece supporting means, and means including a perceptible signaling device associated with and susceptible of actuation by said detectors.

11. The combination of a grinding machine having a pair of closely spaced abrasive wheels and means disposed therebetween for supporting workpieces, with an indicator means comprising a pair of supporting members attachable to said machine, an acoustic pick-up carried by each of said supporting members, a pair of relatively flat fingers each mounted on a respective one of said supporting members, said fingers being interposed between said abrasive wheels and disposed for interception of respective ones of their grinding faces when the latter are in predetermined positions relative to the workpiece supporting means, an amplifying device connected to each said acoustic pick-up, a perceptible signal device connected to said amplifier, and means connecting respective ones of said fingers with corresponding ones of said acoustic pick-ups.

12. The combination of a grinding machine having a pair of spaced apart enclosed abrasive wheels and a pair of vertically spaced guide bars therebetween for channeling workpieces past the opposed grinding faces of said wheels, with a

12

grinding face position indicator comprising a pair of supporting members adjustably attachable to the enclosure for the abrasive wheels, a head on each of said adjusting members, an acoustic pick-up housed within each said head, a pair of resilient fingers disposed for interception of respective ones of the grinding faces when the same are in predetermined position relative to the guide bars, means supporting respective ones of said fingers from corresponding ones of said heads, connecting members interposed between each of said fingers and a corresponding one of said acoustic pick-ups, an amplifier associated with and connected to each said acoustic pick-up, and a loudspeaker connected to said amplifier for reproducing amplified acoustic impulses resulting from contact between said fingers and their associated grinding faces.
